[57] CLAIM

The ornamental design for a spout, as shown and described.

DESCRIPTION

FIG. 1 is a perspective view of a spout showing my new ornamental design;

FIG. 2 is a front view thereof;

FIG. 3 is a back view thereof;

FIG. 4 is a top view thereof;

FIG. 5 is a bottom view thereof; and,

FIG. 6 is a view from the left side thereof taken from the left side of FIG. 1, the view from the right side being a mirror image of FIG. 3.
